(57) **CLAIM**

The ornamental design for a wallpack light fixture, as shown and described.

DESCRIPTION

FIG. 1 is a perspective of a wallpack light fixture;
FIG. 2 is a front elevational view of the wallpack light fixture;
FIG. 3 is a top plan view of the wallpack light fixture;
FIG. 4 is a right elevational view of the wallpack light fixture;
FIG. 5 is a rear elevational view of the wallpack light fixture;
FIG. 6 is a bottom plan view of the wallpack light fixture;
and,
FIG. 7 is a left elevational view of the wallpack light fixture.
The broken line showing in the drawings is included for the
purpose of illustrating portions of the wallpack light fixture
and forms no part of the claimed design.

1 Claim, 7 Drawing Sheets
